UNITED STATES PATENT OFFICE.

ARGYLE CAMPBELL, OF CHICAGO, ILLINOIS, ASSIGNOR TO ENTERPRISE
RAILWAY EQUIPMENT COMPANY, OF CHICAGO, ILLINOIS, A CORPO-
RATION OF ILLINOIS.

METALLIC CAR-ROOF.

No. 824,169.

Specification of Letters Patent.

Patented June 26, 1906.

Application filed October 30, 1905. Serial No. 285,082.

To all whom it may concern:

Be it known that I, ARGYLE CAMPBELL, a citizen of the United States, residing at Chicago, in the county of Cook and State of Illinois, have invented a certain new and useful Improvement in Metallic Car-Roofs, of which the following is a specification.

My invention relates to metallic car-roofs.

The object of my invention is to provide such a roof which can be easily made from a minimum amount of metal to provide a maximum amount of strength, which is efficient in operation, and not readily liable to get out of order.

It also consists in details of construction, which will be hereinafter more fully described and claimed as the specification proceeds.

In the drawings, Figure 1 is a plan view, partially broken away, showing the roof of my invention applied to a car. Fig. 2 is a sectional end view on line 2 of Fig. 1.

It should be understood that the roof of my invention may be applied to the side walls 10 and ends 11 of any of the commercial forms of car, one form of which is illustrated in Fig. 2. Along the inside upper edges of the sides 10 I place longitudinal members 12, of wood or other suitable material, and over these longitudinal members I secure channel-irons 13 or other suitable shapes of metal, preferably with their flanges turned toward the outside of the car, as shown, so as to present a flat surface toward the inside of the car. At intervals along the car I connect these channels 13 by suitable carlines 14, of any convenient shape of metal, and secure the same to the channel-irons 13, by means of the angle-irons 15 and bolts or rivets 16. At the center of the car and running lengthwise of it from end to end I place a U-shaped ridge-pole 17 upon these carlines 14, the bottom of the U resting directly upon the carlines and being secured thereto by any suitable means.

On the upper edges of the U-shaped ridge-pole I form flanges 18, inclined downwardly toward the edge of the car. Upon each of these flanges 18 and its adjacent side of the car I place a continuous flat-metal roof-plate 20, running from end to end of the car, and secure the same by any suitable means to the upper edge 12 of the sides of the car and the end of the car. Over the top edges of the

plates 20, heretofore described, I place an angular cover-plate 21, running lengthwise of the car from end to end, and secure the same to the roof-plates 20 and the ridge-pole flanges 18 by means of the bolts or rivets 22, as shown. By this construction it will be seen that I form a very tight waterproof joint at the apex of the roof and that I have a continuous roof-plate running from the edges of the angular plate 21 to and over the edge of the side of the car, the extreme edges of the plates 20 being bent downward over the same in the portions 24, as shown.

In order to give the roof great rigidity, I place intermediate between the center and the sides of the car channel-irons 25, running lengthwise of the car from end to end, and secure the same to the roof-plates by the bolts or rivets 26 and to the carlines by bolts or rivets 27. I also provide a suitable running-board 28 upon the top of the car for the usual purposes.

It will be seen that by this construction I secure a very rigid roof with the use of a comparatively small quantity of metal and that the same is thoroughly waterproof. While I have referred to the roof-plates as being continuous, I do not necessarily mean that they shall be rolled in one piece, as continuous spliced plates may be used without departing from my invention.

Having thus described my invention, what I claim as new, and desire to secure by Letters Patent, is

1. In a metallic car, in combination with the sides and ends of the car; a plurality of carlines extending crosswise of the car between the sides, a flanged metallic ridge-pole running lengthwise of the car resting upon said carlines, metallic roof-plates extending from end to end of the car secured to said flanges of the ridge-pole and extending over the upper edges of the sides of the car, and an angular cover-plate secured over said roof-plates to said ridge-pole.

2. In a metallic car, in combination with the sides and ends of the car; a plurality of carlines extending crosswise of the car between the sides, a flanged metallic ridge-pole running lengthwise of the car resting upon said carlines, metallic roof-plates extending from end to end of the car secured to said flanges of the ridge-pole and extending over

the upper edges of the sides of the car, an angular cover-plate secured over said roof-plates to said ridge-pole, and supporting members intermediate between the ridge-pole and the upper edges of the sides of the car resting upon the carlines and supporting the roof-plates.

3. In a device of the class described, in combination with the sides, ends and carlines of a car; a U-shaped ridge-pole resting upon said carlines with the base of the U adjacent to the carlines, flanges upon the upper edges of said U-shaped ridge-pole extending angularly therefrom toward the upper edges of the sides of the car, continuous metallic roof-

plates resting upon each flange of the ridge-pole and the adjacent upper edge of the side of the car, an angular cover-plate over the edges of said roof-plates on said ridge-pole, and means for securing said cover-plate, the central edges of said roof-plates and the flanges of said ridge-pole together. 20

In witness whereof I have hereunto subscribed my name in the presence of two witnesses.

ARGYLE CAMPBELL.
